C. A. LEWIS

WINDOW LATCH,

Filed July 3, 1926

FIG. 3

FIG. 4

FIG. 6

Claude A. Lewis INVENTOR.

BY *Jesse P. Stone*
ATTOR

ATTORNEY.

Patented Aug. 28, 1928.

1,681,986

UNITED STATES PATENT OFFICE.

CLAUDE A. LEWIS, OF HOUSTON, TEXAS, ASSIGNOR TO AMERICAN WINDOW COMPANY,
A CORPORATION OF DELAWARE.

WINDOW LATCH.

Application filed July 3, 1926. Serial No. 120,269.

My invention relates to a latch for window sashes.

It is an object of the invention to provide a latch for a window sash which will automatically latch in position when the sash is closed.

It is another object to provide a latch for a window sash having an operating handle thereon which serves as a means of unlocking the sash and also of raising the sash after it is unlocked. It is also desired that the latching handle be adapted for removal when desired and with a minimum amount of manipulation.

It is a further object to provide a latch and a housing therefor which is adapted to be easily and economically applied to the window sash.

Other objects and advantages of the invention will appear from the more detailed description which follows.

Referring to the drawing herewith, Fig. 1 is a central vertical section through the broken lower end of the window sash and the sill showing my invention applied thereto. Fig. 2 is a similar view of the latch and the housing detached and illustrating the latch in a different position. Fig. 3 is a front view of the housing and latch showing the handle removed. Fig. 4 is a rear elevation of the handle removed. Fig. 5 is a broken horizontal section illustrating the attachment of the handle to the housing, said section being taken approximately on the line 5—5 of Fig. 1, the latching means being omitted. Fig. 6 is a front elevation of the latching plate to be fixed upon the window casing to receive the latch. Like numerals of reference are employed to designate like parts in all the views.

In Fig. 1, I have shown the window sill 1 and the stool 2 in broken section, the side of the stool adjacent the sill being vertical at 3 and having a recess 4 to receive a locking plate 5. The shape of this plate is shown best in Fig. 6. It has two openings 6, one at each side, to receive screws by means of which it is secured to the stool of the window. The lower portion is cut away centrally at 7 to provide an opening to receive the latch. Above this opening the plate is beveled upwardly at 8 and the central portion of the plate is extended slightly higher than are the two sides adjacent the beveled portion, as shown at 9.

The window sash has its lower transverse member 10 shaped to fit the sill 1 and is therefore beveled downwardly from the inner side. Its upper side is grooved at 11 to receive the glass 12.

On the inner side of the sash and centrally thereof is cut a diagonal recess 13. This recess is of sufficient width to receive the housing 14 for the latch. Said housing is made up of sheet metal, the inner face of which is inclined to fit within the recess 13, the lower side being inclined upwardly toward the inside, thus providing a bottom wall 15 of the same inclination as the sill. The upper end of the housing is provided with a forwardly extending flange 16 and the sides of the housing toward the upper portion thereof are extended laterally to widen the housing at the forward end, as shown at 17 in Fig. 5, and the forward edge of the side members are bent outwardly to form flanges 18 which form slideways for the handle plate 19. These laterally extending flanges 18 are cut away centrally at 20 so as to receive the handle plate, as will be later described. The enlarged portion 17 of the housing projects forwardly from the sash as shown in Fig. 1.

Pivoted within the narrow portion of the housing is a latch member 21. It pivots upon a pin 22 at the upper shallow portion of the housing, said pin extending from one side wall to the other. The rearward side of the latch member is approximately straight to a point adjacent its lower end, where it is rounded off at 23. The forward side of the lower end has a beveled or cam face 24 and above said cam face is a shoulder 25 formed by a recess cut within the forward face of the latching dog. Above this shoulder, the face is beveled forwardly at 26 and above this beveled portion is an upwardly extending point 27. To the rear of this point is a comparatively deep recess 28, above which the forward face is beveled upwardly at 29 to co-operate with the operating handle. The upper end of the latching dog has two forwardly extending arms 30 between which is a rod-receiving recess 31.

The handle plate 19 is of approximately the same length as the upper widened portion of the housing. Its edges are curved inwardly at each side to form a channel 41 to fit about the flanges 18 to slide thereon. The side flanges are cut away centrally at 32 to provide space to receive one pair of the sides 110.

flanges 18 of the housing. The upper end of the plate is curved forwardly and rounded off at 33 to provide a handle. The lower end is bent inwardly at right angles to the plate 5 to form a base 34 and the inner edge of the base is inclined downwardly at 35 to co-operate with the latch. Mounted in the base 34 is an upright pin or rod 36, the upper end of which is curved forwardly and extended 10 through the plate at 37 and riveted in position. About the rod 36 is a spiral spring 38, which, when the handle is raised, is adapted to contact with the arms 30 upon the latching dog. The housing is secured in position in 15 the recess 13 by screws 40 or any other desired means.

When the window sash is in raised position, the handle plate 19 may be in the position shown in Fig. 1. The latching dog may then 20 extend downwardly, as there shown, the exact position being immaterial. When the sash is lowered, the base 34 of the handle plate will contact with the upper edge 9 of the latching plate 5 and be raised upwardly toward the full line position shown in Fig. 1. The spring 38 will engage the arms 30 upon the latching dog and hold it forwardly, the beveled end 24 will engage upon the beveled 25 face 8 of the latching plate and the latch will be forced inwardly, after which it will be pressed back under the lower shoulder of the recess 7 in the latching plate. It will be noted that the said lower shoulder is beveled upwardly at a slight angle on its side toward 30 the window stool so that the shoulder 25 of the latch will have a sharp frictional engagement with the latch to prevent its accidental unlatching. The beveled face 26 of the latch will fit against the wall 8 of the plate 5 and the point 27 of the latch will bear against the lower face of the base 34 of the handle plate. The raised portion 9 of the latching plate will provide space for the movement of said point to latching position. When the latch is to be 35 disengaged and the sash raised, the handle 33 is pulled upwardly. The end 35 thereof will contact with the face 29 of the latch and force the latch inwardly, releasing it from the latching plate with the latch in the dotted line position of Fig. 1; the handle may be 40 then raised further until the pin 36 strikes the upper wall 16 of the housing and any further upward pull will raise the sash.

When the handle plate is to be removed to 45 clean or oil the lock or paint the sash, the window is raised, the handle is lifted to release the point 27 from the handle and the latch and then pushed inwardly so that the handle may be dropped to Fig. 2 position, 50 after which the flanges 18 will release the channels 41 of the plate and the handle may be then pulled forward and removed. When it is again replaced, the handle plate is placed in the Fig. 2 position and raised up to 55 engage the channels 41 with the flanges 18

and the rod 36 within the recess 31 of the latch. When the handle is then raised into Fig. 1 position, the latch will be thrown forwardly and the point 27 will engage behind the edge 35 of the handle plate so that the 70 latch cannot move inwardly away from the plate, beyond the Fig. 1 dotted line position. This will assure the engagement of the latch with the latching plate when the sash is closed, and also prevents accidental removal 75 of the handle plate.

The shape of the latch housing will be of advantage in that a diagonal cut in the sash of the proper width is all that is necessary to receive it. It is easily secured in position by 80 screws before the handle plate is placed on the housing. The latch engages the plate automatically and releases automatically when the handle 33 is raised to elevate the sash.

The action of the latch is simple and positive, and the construction is economical to manufacture. It is easy of access from the inside but will resist all attempts to raise the sash from the outside.

Having thus described my invention, what I claim as new and desire to protect by Letters Patent is:

1. In combination with a window sash and casing, means for latching the window sash to the casing, comprising a shouldered plate on said casing, a pivoted latching dog on said sash, a handle slidable relative to said dog, means on said handle co-operating with said dog to force it into latching engagement with said plate, and means on said handle to throw said dog out of latching position when said handle is raised to elevate said sash.

2. In combination with a window sash and casing, means for latching the window sash to the casing, comprising a shouldered plate on said casing, a pivoted latching dog on said sash, a handle slidable relatively to said dog, means on said handle co-operating with said dog to force it into latching engagement with said plate, and means on said handle to throw said dog out of latching position when said handle is raised to elevate said sash, said handle being removable from said sash.

3. In combination with a window sash and casing, means for latching the window sash to the casing, comprising a shouldered plate on said casing, a pivoted latching dog on said sash, a handle slidable relative to said dog, arms on said dog and a spring on said handle engaging said arms to force said dog resiliently into latching engagement with said plate, and means on said handle to throw said dog out of latching position when said handle is raised to elevate said sash.

4. In combination with a window sash and casing, means for latching the window sash to the casing, comprising a shouldered plate on said casing, a pivoted latching dog on said

sash, a handle slidable vertically relative to said dog, arms on said dog and a spring on said handle engaging said arms to force said dog resiliently into latching engagement with said plate, and means on said handle to throw said dog out of latching position when said handle is raised to elevate said sash, said means also serving to limit the movement of the dog from latching position.

5 10 5. In combination with a window sash and casing, a latching plate on said sash, a housing set in said sash adjacent said plate, a latching dog pivoted to move in said housing, a shoulder on said dog to engage said plate, a handle closing the forward side of said housing, means on said handle to force said shoulder into engagement with said plate, and means to limit the movement of said dog from latched position.

15 20 6. In combination with a window sash and casing, a latching plate on said sash, a housing set in said sash adjacent said plate, a latching dog pivoted at its upper end to move in said housing, a shoulder on said dog at its lower end to engage said plate, a handle closing the forward side of said housing, means on said handle to force said shoulder into engagement with said plate, and means on said handle to limit the movement of said dog from latched position.

25 30 7. In combination, a window casing, a window sash, a latching plate on said casing

having a recess to receive a latch, a triangular-shaped housing set in a diagonally-cut slot in said sash adjacent said plate, and a 35 latching dog pivoted to move in said housing and engage in said recess in said plate, a handle slidable on said housing and engaging said dog, said handle being removable from said housing when said handle is adjusted vertically thereon.

40 45 8. In combination, a window casing, a window sash, a locking plate on said casing having means thereon to engage a latch, a triangular-shaped housing set in a diagonally-cut slot in said sash across the forward side at the lower end thereof adjacent said plate, and a latching dog pivoted to move in said housing and engage said plate.

45 50 9. In combination, a window casing, a window sash, a latch receiving plate on said casing, a housing in said casing adjacent said plate, a latching dog pivoted at its upper end in said housing, the lower end of said dog having a plate engaging shoulder, a handle 55 slidable on said housing, a spring on said handle engaging the upper end of said dog to press said dog into latching engagement with said plate, said dog being released when said handle is raised.

55 60 In testimony whereof I hereunto affix my signature this 29 day of June, A. D. 1926.

CLAUDE A. LEWIS.
